UNITED STATES PATENT OFFICE.

GUSTAV H. WERNER, OF ST. LOUIS, MISSOURI.

ICE-TONGS.

SPECIFICATION forming part of Letters Patent No. 329,523, dated November 2, 1885

Application filed September 10, 1885. Serial No. 176,752. (No model.)

To all whom it may concern:

Be it known that I, GUSTAV H. WERNER, a citizen of the United States, residing at St. Louis, in the State of Missouri, have invented 5 certain new and useful Improvements in Ice-Tongs, of which the following is a specification.

My improvements relate to ice-tongs; and they consist in the combination of a saw and a 10 splitter with a pair of ice-tongs to make an improved combination-tool.

To more fully describe the construction and operation of my invention, reference is had to the accompanying drawing, in which the figure 15 represents a perspective view of a pair of ice-tongs with my improvements shown.

A represents a pair of ice-tongs. B and C are the two arms. One of these arms, B, I provide with teeth *a* along its outer edge to 20 form a saw, and is intended to be used for sawing ice. The other arm, C, I construct to form a blade, having its sharp edge *b* outward, and is intended to serve as a splitter to split the ice after it is sawed. The tongs them-

25 selves will serve to take hold of the ice with and to carry it by, and have the points or prongs *c* and handles *d*, as usual.

Thus my improved tongs form and serve as three useful and necessary tools combined in one, and are specially intended for boarding- 30 houses, restaurants, saloons, and families.

The tool may be made of wrought or malleable cast-iron, as desired.

What I claim is—

1. The combination of a pair of ice-tongs, 35 A, with the saw-shaped arm B, substantially as herein shown and described, to form a new combination-tool, as and for the purpose set forth.

2. The combination of a pair of ice-tongs, 40 A, with the saw-shaped arm B and blade-shaped arm C, substantially as herein shown and described, to form a new combination-tool, as and for the purpose set forth.

GUSTAV H. WERNER.
